PROTECTIVE SYSTEM

Hermann Neugebauer, Berlin-Spandau, Germany, assignor to Westinghouse Electric & Manufacturing Company, East Pittsburgh, Pa., a corporation of Pennsylvania

Application August 5, 1933, Serial No. 683,893
In Germany August 8, 1932

27 Claims. (Cl. 175—294)

My invention relates to protective systems for transmission lines.

Numerous protective systems have been proposed, in which relaying devices are arranged at the end of the protected line-section, the relaying devices being connected to one another through an auxiliary communicating channel such as a high-frequency path, and being brought into such mutual relationship that the opening of the circuit-interrupter at each end of the line-section depends not only upon the operation of the relay in the neighborhood of the switch, but also upon the operation of the relaying devices at the other end of the line-section. Such section-protective systems may be carried out in various ways; for instance, in such manner that a signal coming over the communicating channel is necessary, if the circuit-interrupter is to be opened, or in such manner that a signal coming over the auxiliary channel is utilized to prevent the opening of the circuit-interrupter. The signal may consist in either the transmission or the interruption of a signalling current in the communication channel.

The invention, in one of its embodiments, relates to protective systems of the last-mentioned character, in which, if the signal from the remote end of the line-section is not transmitted, the opening of the circuit-interrupter switch is made possible, or caused to take place in the shortest possible time.

According to the invention, the protective devices which are provided to transmit a high-frequency signal from one end of the section to the other, for indicating the operation of a relay, are continuously controlled or tested as to their operativeness. To this end, I provide a relaying device which operates as a result of a failure of the carrier means. The carrier means comprises a device which controls the transmission of the signal, a carrier-current transmitter or power-source for the signal to be transmitted and, in case auxiliary lines are provided, these auxiliary lines, over which the signal is to be transmitted.

If this carrier system fails to operate, it may happen that the circuit breaker at the other end of the protected line-section may be opened by a false relaying operation if, for instance, an over-current occurs at this other end and the direction of energy-flow is into the protected line-section at said other end. The possibility of this false relaying operation is due to the fact that the individual relaying devices which control the circuit-interrupters in a protective system utilizing an auxiliary communicating channel are not

at all selective in and of themselves, but become selective only by comparing the current-conditions at one end of the line-section with the current-conditions at the other end. If the auxiliary channel which is necessary for effecting this comparison should fail, faulty operations are unavoidable.

According to the present invention the protective system which depends upon the operations of the relays at both ends of the line-section is put out of operation as soon as it is ascertained that the transmitter is failing to transmit. The putting out of operation is retarded for a certain time, in order that the protective system is not put out of operation in such cases in which it is about to operate. An indication of a failure of the carrier system may be obtained from the fact that an operation of the carrier system, which should take place only if a fault has occurred somewhere in the protected section, is not accompanied by the operation of the tripping relay of the protective system. If, for instance, the tripping relay is an over-current relay, and if the opening of the circuit-interrupter depends upon the fact that no carrier-current signal arrives from the remote end of the section to block said opening in the case of a fault occurring outside of the protected section, the non-transmission of the blocking signal would not alone cause the opening of the circuit-interrupter. The very fact, therefore, that the blocking signal fails to flow as circulating current, while the tripping relay is not actuated, shows the occurrence of a failure of the circulating-current circuit. In this case, according to the invention, an auxiliary relay is operated, which puts the entire line-section protective system out of operation after a predetermined time-delay for which the auxiliary relay is adjusted. The subsequent fault-responsive disconnection of the line-section would have to be effected, in this case, by a second protective system, if any, for instance, by a protective system with inverse or definite time grading.

In the accompanying drawings, Fig. 1 is a diagrammatic view of circuits and apparatus illustrating my invention as applied to a line-section of a transmission line; Fig. 2 is a similar view of a modified construction applied to a plurality of successive sections of a longer transmission line; Fig. 3 is a single-line diagram of a further modification applied to a multi-circuit transmission line; and Fig. 4 is a diagrammatic view of circuits and apparatus illustrative of the equipment at one of the sectionalizing stations in Fig. 3.

As disclosed in Fig. 1, my invention is asso-

- ciated with a three-phase high-voltage transmission system having a line-section 4 which is to be protected. The line-section is provided, at each end, with a circuit-interrupter 1 which is to be automatically opened by a trip coil 2 as soon as a fault occurs in the section. In the embodiment of my invention shown in Fig. 1, a communicating channel is provided between the two ends of the line-section, in the form of a high-frequency path which extends from earth through a coupling capacitor 3 and one of the line-conductors of the protected line-section 4.
- The relaying station at each end of the protected line-section has any suitable power-directional tripping-relay R which is illustrated as being so connected that it responds to the direction of the negative-phase-sequence power-component when there is an unbalanced fault within the protected line-section. To this end, the power-directional relay R is energized by a negative-phase-sequence current-network I_2 and by a negative-phase-sequence voltage-network V_2 . Each relaying station further includes a transmitter S and a receiving relay E. The transmitter in the station at the left-hand end of the line-section 4 is tuned, for instance, to a frequency of 100,000 cycles, whereas the transmitter at the other end is tuned to 100,500 cycles. The transmitters at both relaying stations normally operate continuously, so that the difference between the two transmitting frequencies (500 cycles) will normally be continuously available to energize both receiving relays E, as will subsequently be described.
- According to the embodiment of my invention shown in Fig. 1, each transmitter S is connected to one of the line-conductors of the section 4, through a normally closed relay-contact 5, and also through a transmitter-coupling transformer 6, a receiver-coupling coil 9, and the previously mentioned coupling capacitor 3. Each transmitter S is permanently connected, also to a coupling coil 7 which is inductively related to a coil 8, to which the receiving relay E is connected. The coil 8 is also inductively related to the receiver-coil 9 in series with the coupling capacitor 3. The high-frequency current coming to each relaying station from the distant end of the section thus acts on the coil 8 through the coupling capacitor 3 and the receiver-coupling coil 9. Consequently, the coil 8 has induced therein a voltage of a frequency equal to the difference between the frequencies of the two transmitters E. The voltage induced in the coil 8 operates the receiving relay E only when this voltage has that frequency to which the relay E, or a series-connected filter F, is adjusted, that is, the beat-frequency of both transmitters which are associated with the protective relays of the protected line-section 4.
- As soon as the receiver relay E is energized it opens two contacts E_1 and E_2 . When the receiver relay E is deenergized, its contact E_1 completes a partial circuit which will result in energizing the trip coil 2 as soon as the power directional relay R has closed its normally open contact R_1 , provided that the normally closed contact Z_1 of a timing relay Z is closed. This timing relay Z is energized, as soon as the receiver relay E is deenergized, by the receiver-relay contact E_2 , but the time-relay contact Z_1 does not open for a certain time, determined by a dashpot Z_2 . Thus, if the receiver relay E remains deenergized for this certain predetermined time, without an actuation of the directional tripping-relay R, the time-relay contact Z_1 opens and locks out the carrier-

current responsive relaying equipment until proper carrier operation is again restored.

In the illustrated embodiment of my invention, therefore, the protective system is carried out in such manner that the opening of each circuit-interrupter 1 is normally prevented by a continued transmission of high-frequency current from both ends of the section, which energizes a beat-frequency receiver relay E at each relaying station. In the event of the failure of the beat-frequency, and in the further event of the energization of the directionally responsive tripping-relay R at either relaying station, the corresponding circuit breaker 1 will be opened.

If a fault occurs in the line-section 4, the power-directional relays R at both ends of the line-section are actuated. The tripping circuit as above described is partly completed through the directional-relay contact R_1 , the circuit being finally completed as soon as the normally energized receiver relay E ceases to receive its beat-frequency current, so as to close its contact E_1 . The power-directional relay R has also a second normally open contact R_2 , which closes in response to an unbalanced fault in the protected line-section and energizes an auxiliary relay 10 which carries the normally closed contact 5 in the circuit of the transmitter-coupling transformer 6. Upon the occurrence of a fault in the protected section, therefore, the transmitter S at each relaying station continues to operate as under normal fault-free operating conditions; but the directional relay R at each end operates, energizing the auxiliary relay 10 and causing the contact 5 to be opened, so that the transmitter-energy is not transmitted to the high-voltage line-section 4 at either end thereof. The influence exerted by each transmitter E on its local receiver-actuating coil 8 is, however, not changed, so that the coil 8 at each station receives energy from only its own carrier-frequency transmitter, although it has no beat-frequency voltage capable of energizing the corresponding receiver-relay E. In this manner, each receiver-relay E is deenergized and closes both contacts E_1 and E_2 thereof. Until the timing relay Z picks up its contact Z_1 , after its predetermined time-delay, the energizing circuit for the trip coil 2 is closed, and hence the circuit breaker 1 opens at each end of the protected line-section.

If the fault is not in the protected line-section 4, but in a neighboring section, for instance in the line-section 20 on the left-hand side of the line-section 4, the receiver-relay E at the right-hand end of the protected line-section 4 responds to the inwardly flowing power at this point, and partially closes the tripping circuit at this end of the protected line-section, and it depends only upon the contacts E_1 of the receiving relay E at this station to determine whether the tripping action shall take place or not. At the left-hand end of the protected line-section 4, however, the power is flowing outwardly, so that the directional relay R at this end does not respond. Thus the contact 5 of the auxiliary relay 10 at this end remains closed, so that the transmitter E at the left-hand end of the protected line-section 4 continues to transmit its high-frequency energy to the right-hand end, where the receiving relay E is consequently supplied with a voltage having the beat frequency corresponding to its tuning. In this manner, the contacts of the receiving relay E remain open at the right-hand end of the protected section, so that there is no tripping action at that end. At the left-

hand end of the line-section 4, the receiving relay E is impressed with only the high-frequency carrier-current of its own transmitter S, because the high-frequency carrier-current of the transmitter S at the right-hand end is cut off by the relay 10 at that end. This deenergizes the left-hand receiver relay E and closes its contacts E₁, but the tripping circuit at this station is not completed because of the open contact R₁ of the unactuated power-directional relay R.

If either one or both of the transmitters E should fail to operate for any reason, a voltage of the beat-frequency cannot result in either one of the receiver relays E, so that these receiver relays in both relaying stations close their contacts E₁ and E₂. As long as the directional tripping relay R at either end of the line-section does not close its contact R₁, the failure of the voltage of beat-frequency is evidently not caused by a line-fault, but by a fault in the carrier-current system. Consequently, the receiver relays E permanently close their contacts, and the timing relay Z picks up and opens its contact Z₁. Since this timer-relay contact Z₁ is series-connected with the trip coil 2, the entire relaying device is thus rendered inoperative, because the selectivity of the entire relaying device depends upon the fact that a mutual cooperation with the relay-device at the other end of the section must be brought about before the opening of the circuit-interrupter 1. A faulty opening of a line circuit-interrupter cannot now occur as a result of a failure to receive a signal from the other end of the line-section at a time when the fault-energy at said other end is flowing out of the protected line-section.

In the illustrated embodiment of my invention, as shown in Fig. 1, a single capacitor 3 is schematically shown as the coupling means. In most cases, instead of a simple capacitor 3, a more complicated filter-device is employed, which is tuned to the carrier-current frequencies employed in the protection of the line, and which has a range such that frequencies of a high order of magnitude are permitted to pass. It is preferable to choose high frequencies so as to reduce the dimensions of the transmitting and receiving devices, as well as the filters. For instance, a carrier-current frequency of 100,000 cycles may be chosen for one end of a protected line-section, and 101,000 cycles for the other end, so that the beat-frequency is extremely small as compared to the carrier-current frequencies employed. It is preferable to choose, for the relaying devices of successive line-sections, frequencies differing slightly from one another, for instance, for two successive line-sections, the frequencies 100,000, 101,000, and 103,000, 104,000, respectively, thus providing a double-frequency (or any different) beat of 2,000 cycles between the two transmitter-frequencies in alternate sections, so as not to conflict with the operation of the 1,000-cycle beat-frequency relaying equipment of the intervening sections.

By connecting the receiving relays to a filter which has a correct range for the beat-frequency employed, a very high selectivity is obtained in regard to the high-frequency currents occurring in the high-voltage transmission lines. At the same time, my system avoids the defects which have been encountered in the best-known prior systems, in which it was essential to prevent the spreading out of the high-frequency waves beyond the limits of the several line-sections, but in which this could be only im-

perfectly accomplished by means of blocking-circuits which were built into the high-voltage transmission line and dimensioned for the passage of heavy currents. By the use of the beat frequency it is possible to employ relatively narrow frequency bands, making it possible to use, for relaying purposes, the intervals which exist between the wave-bands of the telephone, remote-metering and telegraph communication channels which may be also operated over the same high-voltage transmission lines.

As shown in Fig. 2, it is possible to reduce the number of different frequencies, that is to say, to reduce the total range of frequencies, necessary for the protection of several successive line-sections of a transmission line by using a single transmitter in each relaying or sectionalizing station for two purposes; namely, for the protection of both the right-hand line-section and the left-hand line-section. In this case, the manner of connection must be alternated, however, by causing, for instance, the high-frequency carrier-current to prevent the opening of the circuit-interrupter for the line-section on the right-hand side of the relaying station and to open the circuit-interrupter for the line-section on the left-hand side of the station, or vice versa. For various successive sections the number of transmitters, that is, the number of different carrier-current frequencies, will not be greater, therefore, than the number of switching or sectionalizing stations.

In Fig. 2 I have shown four successive line-sections of a transmission line, as indicated at 21, 22, 23 and 24, separated by sectionalizing relay-stations 25, 26 and 27, respectively. Only one end of each of the sections 21 and 24 is shown in Fig. 2, the two central sections 22 and 23 being shown complete. At each end of each line-section, there is a circuit interrupter as indicated at 28, 29, 30, 31, 32 and 33, respectively, said circuit breakers being provided with trip-coils 28' to 33'.

For each end of each line-section there is also provided a directional relay, as indicated at 34, 35, 36, 37, 38 and 39, respectively. These directional relays, as in the case of the directional relays R₁ to R₄ in Fig. 1, are each biased to a normal or unactuated position, from which they are moved only in response to power, or fault magnitude, flowing in the direction from the sectionalizing station into the line-section in question. The directional relays are shown in their normal or unactuated positions. These directional relays may be connected in any known or desired manner of connection, either utilizing the phase-sequence networks of Fig. 1, so as to respond to a polyphase phase-sequence quantity, or connected so as to respond to the conditions in individual phases. As the particular method of connecting the directional relays is not essential to an understanding of the modification utilizing a single transmitter per station, instead of two transmitters as in Fig. 1, I have simplified Fig. 2 by showing only the phase-C directional relays 34 to 39, it being understood that similar relays will be provided for each phase for which protection is required, or that the directional relays may be connected through phase-sequence networks as shown in Fig. 1.

Each of the three successive sectionalizing stations 25, 26 and 27 is provided with a single carrier-current transmitter, as indicated at 40, 41 and 42, these transmitters being tuned respectively for 101,000 cycles, 103,000 cycles and 104,000 cycles.

Each of the sectionalizing stations 25, 26 and 27

27 of Fig. 2 is provided, as in Fig. 1, with a coupling capacitor 3, a transmitter-coupling transformer 6, a receiver-coupling transformer 7, 8, 9, a filter F passing the heat-frequency of 1000 cycles, a receiver-relay E, and a timing relay Z. At the switching station 25, however, the receiver relay E and the timing relay Z are associated with the directional element 34 which is responsive to fault-power flowing to the left, in line-section 25. 10 21. In the next switching station 26, the receiver relay E and the timing relay Z are associated with the directional element 37, which is responsive to fault-power flowing to the right, in line-section 23. In the next switching station 27, the receiver relay E and the timing relay Z are associated with the directional element 38, which is responsive to fault-power flowing to the left, in line-section 23. These three receiver relays E serve to protect only one of the two line-sections connected to 20 each switching station, and this protection is similar to that which has already been explained in connection with Fig. 1.

To protect the other line-section at each of the switching stations 25, 26 and 27, in Fig. 2, I have shown other receiver relays, as indicated respectively at 43, 44 and 45, which are utilized to directly trip the corresponding circuit-interrupters 29, 30 and 33, respectively, the receiver-relays being supplied with tripping contacts 43', 44' and 30 45', for this purpose. Since the receiver relays 43, 44 and 45 are utilized to actually open the associated circuit breakers when the receiver relays are energized, the connections must be such as to fulfill the conditions set forth in connection with 35 Fig. 1, namely, that the fault-power direction must be into the protected line-section at each end thereof, as indicated by the condition of the carrier-current channel and by the condition of the directional relay at the switching station in question. The energizing coils of the receiver relays 43, 44 and 45 are thus connected to their associated filters 43'', 44'' and 45'', and their tripping-contacts 43', 44' and 45' are connected, as in Fig. 1, in series with the contacts 35', 36' 45 and 39' of the corresponding directional relays 35, 36 and 39, respectively.

It will be noted that the frequency-difference between the transmitters 40 and 41 of stations 25 and 26 is different from that between the transmitters 41 and 42 of stations 26 and 27, thereby avoiding conflict, as indicated in the discussion of Fig. 1. The filters 43'', 44'' and 45'' are therefore tuned to pass 2,000 cycles, rather than 1,000 cycles, so as to respond selectively to carrier-current transmission at the remote end of only the respective sections (21, 22 and 23) in which the receiver-relays 43, 44 and 45 are located.

The operation of the system shown in Fig. 2 is as follows. The connection and disconnection 60 of the several transmitters 40, 41 and 42 to the transmission-line sections 21, 22, 23 and 24 is made responsive to the directional relays 34, 37 and 38, respectively, each transmitter being connected to the transmission line at all times except when its associated directional relay is moved to its actuated position, in which case, it energizes a relay 34', 37' or 38', as the case may be, thereby opening the normally closed contact 5 of the latter, and interrupting the transmission 65 of carrier current at that station, as in Fig. 1.

In line-section 23 in Fig. 2, the protection is precisely the same as that which is shown in Fig. 1, so far as the operation of the carrier-current is concerned; that is, the normally maintained carrier-current is interrupted only

in response to fault-current flowing into the protected line-section 23, so that the receiver relays E, at stations 26 and 27, are deenergized only when power of fault-magnitude is flowing into the far end of the protected line-section 23, thereby causing the receiver relays to drop and close their back contacts E₁ and E₂, precisely as has been described in connection with Fig. 1.

The line-section 22 in Fig. 2 is somewhat differently protected. In this case, the normally maintained carrier-current is interrupted only in the event of fault-current-flow in the direction out of the protected line-section 22, so that the respective receiver filters 43'' and 44'' at stations 25 and 26 will fail to receive their beat-frequency of 2,000 cycles, only when power of fault-magnitude is flowing out of the far end of the protected line-section. In the event that a current of fault-magnitude flows into the section 22 at either end, say, at station 25, the corresponding directional relay 35 will respond, closing its tripping contact 35'.

If the fault-current flow is caused by an internal fault within the protected line-section 22, there will be an inwardly flowing fault-current at the other end 26 of the line-section 22, so that any fault-current flowing in the directional relay 37 in the succeeding line-section 23, at said end or station 26, will be in a direction out of said succeeding line-section 23, so that the directional relay 37 will not respond. Hence, the 103,000-cycle carrier-current will not be removed from the protected line-section 22 at the far end 26 thereof, and the receiver-filter 43'' at the end 25, where the relaying performance is being considered, will remain energized with its beat-frequency of 2,000 cycles, keeping the receiver relay 43 energized, and keeping its tripping-contact 43' closed. As soon, therefore, as the directional relay 35 closes its contact 35', a tripping-circuit will be completed through the contacts 35' and 43', to trip the circuit-breaker 29.

If, however, the power-in fault-current-flow in the directional relay 35 had been caused by an external fault, not in the protected section 22, but in some section beyond it, then there would have been a similar fault-current-flow into the next adjacent line-section 23, instantly actuating the directional relay 37, and removing the 50 103,000-cycle carrier-current from the protected line-section 22 at station 26. This would instantly deenergize the receiver-filter 43'' at the station 25, where the relaying operation is under consideration, deenergizing the receiver relay 43, and opening its tripping-contact 43', so that, by the time that the directional element completed its response to the power-in fault-current there-in, and closed its contact 35', the receiver-filter 60 43'' would have become deenergized, and the tripping-circuit would have been opened at the receiver-relay contact 43', so that the circuit-breaker 29 would not be opened.

In the line-sections 22 and 24 of Fig. 2, where the receiver relays 43, 44 and 45 must be energized in order to trip their associated breakers 29, 30 and 33, respectively, these receiver relays can be energized only when the carrier-current transmitters at the two ends of the protected 70 line-section are both functioning, as otherwise the said receiver relays 43, 44 or 45 would not receive any energy from their respective filters 43'', 44'' or 45''. Hence it is not necessary to make any special provision, such as the timing 75

relays **Z** of Fig. 1, to guard against the contingency of carrier-current failure in the line-sections **22** and **24** of Fig. 2.

In the system shown in Fig. 2, it will readily be understood that the line-section **21** is protected similarly to the line-section **23**, with a 1,000-cycle beat-frequency between the transmitters at its two ends, and with carrier removed by "power-in" flow of fault-current; while the line-section **24** is protected similarly to the line-section **22**, with a 2,000-cycle beat-frequency between the transmitters at its two ends, and with carrier removed by "power-out" flow of fault-current.

Figs. 3 and 4 show another modification in which the switching operations may be carried out with only one high-frequency transmitter at each switching station. This system utilizes a transmitter in each switching station, with a separate modulation-device for each line-section to be protected at that station. The modulations consist of superposed frequencies so chosen that, for each modulation-wave, there will be only one receiving relay tuned to that modulation-frequency, in one of the lines under consideration, and this receiving relay continuously determines the existence or non-existence of said modulation-wave and prevents the opening of its associated circuit-breaker as long as the existence of the corresponding modulation-frequency is indicated by the relay. Even if numerous lines leave a station, it is possible to carry out this system with only one high-frequency generator which produces the carrier wave at each station, the different high-frequency generators being preferably of different frequencies. At each relaying station, tuned high-frequency receiving-circuits are provided, as by means of the coupling capacitors **3**, or more elaborate tuning devices, as previously explained, and a time-relay is also provided, for instance as shown in Fig. 1, which renders the section protective device inoperative if a modulation wave fails for a certain time, provided that the other requisites for the disconnection of the section are not fulfilled simultaneously during this period in the relaying station under consideration.

In Fig. 3 is shown a single-line diagram of such an embodiment of my invention, in which it is assumed that the lines are paralleled at each relaying station **A**, **B** and **C**. A two-circuit transmission system is indicated, in which there are two parallel line-sections **71** and **72** between stations **A** and **B**, and two parallel line-sections **73** and **74** between stations **B** and **C**. At each station, there is a high-frequency transmitter, which is indicated at **75** in Fig. 4, for station **B**, and the output of this transmitter is modulated in accordance with a particular frequency for each line-section connected to the station bus. The modulators are indicated in Fig. 3 by triangles drawn above each line-section at each station, the triangles or modulators being denoted by the letter **M**, with a subscript indicating the frequency, which varies from 400 cycles to 750 cycles, in 50-cycle steps. Below each line-section, in Fig. 2, the receiver relays at the several stations are indicated by circles designated by the letter **E**, with subscripts indicative of the frequency to which they are responsive.

As shown in Fig. 4, the transmitter **75** located in station **B** transmits a high-frequency carrier current of, say, 100,000 cycles, which is modulated by means of the alternating-current modu-

lating generators **M₅₀₀**, **M₅₅₀**, **M₆₀₀**, and **M₆₅₀**. These modulating generators are connected to a modulating circuit **76** of the transmitter **75**, through individual filters **77**, **78**, **79** and **80**, which are tuned to the respective modulation-frequencies, and also through normally closed relay-contacts **81**, **82**, **83** and **84**, respectively, so that, in normal operation, all four modulation-frequencies are impressed upon the carrier-current wave. This modulated carrier-current is superimposed upon the transmission system by means of the transformer **6**, which is connected in series with the grounded circuit including the coupling capacitor **3**.

Fig. 4 also shows the receiver circuit provided at station **B**, the same being connected to the grounded coupling circuit including the coupling capacitor **3**, by means of a transformer **85**. The received current is demodulated by means of a rectifier **86**, and by this means, demodulated current is supplied to a receiver-circuit **87**, to which the several receiver relays **E₄₀₀**, **E₄₅₀**, **E₇₀₀** and **E₇₅₀** are connected, through their respective filters **88**, **89**, **90** and **91**.

In Fig. 4, the paralleling bus **92** at station **B** is connected to the ends of four line-sections **71**, **72**, **73** and **74**, each having its individual modulator and receiver, as indicated more clearly in Fig. 3. As the equipment for each line-section is the same, except for the tuning, a description and illustration of one will suffice for all, and hence I have shown, in Fig. 4, the equipment for only the line-section **74** at station **B**. The directional element **37** for this line-section is indicated schematically in accordance with the method of illustration adopted in Fig. 2, and it has normally closed back-contacts **84** which normally keep the 650-cycle modulator-generator **M₆₅₀** connected to the modulating circuit **76** of the carrier-current transmitter **75**. The directional element **37** has normally open front-contacts **93** which are closed only when current of fault magnitude flows from the bus **92** into the protected line-section **74**. These directional-relay contacts **93** are connected in the tripping circuit of the circuit breaker **94** which is located in station **B** in the line-section **74**. This tripping circuit also includes the back-contacts **95** of the receiver-relay **E₇₅₀**, and the back-contacts **Z₁** of the associated timing relay **Z₇₅₀** which is controlled by the receiver-relay as in Fig. 1.

The operation of the system shown in Figs. 3 and 4 is similar to that shown in Fig. 1, except that the modulation frequencies of demodulated receiver-waves are utilized, rather than beat-frequencies, for the purpose of determining the condition of the directional relay at the other end of the protected line-section. This modulated-carrier response may be either to the "power-in" flow or the "power-out" flow at the remote end of the protected line-section. In the particular embodiment shown in Figs. 3 and 4, the 750-cycle modulation which is characteristic of the remote end of the protected line-section **74** is maintained at said remote end at all times except when current of fault-magnitude is flowing in the "power-in" direction at that end, and hence the receiver-relay **E₇₅₀**, which responds to this modulation, is a lock-out relay which prevents the tripping of the circuit breaker **94** as long as this receiver-relay is energized, this function being accomplished by the opening of the back-contact **95** of the relay whenever the relay is energized. It is believed that the operation of the system shown in Figs. 3 and 4 will now be

obvious in view of the explanations given in connection with Fig. 1.

I claim as my invention:

1. A carrier-current protective system for a transmission-line section, comprising two sources of carrier current of different frequencies coupled to the line-section, one at each end thereof, means for controlling the transmission and non-transmission of carrier at each end in some manner in accordance with the occurrence or non-occurrence of predetermined line-circuit conditions at that end, and means at each end, selectively responsive to the beat-frequency of the two carrier-current sources, for obtaining an indication of the line-circuit conditions at the other end of the line-section.

2. A carrier-current protective system for a transmission-line including a line-section having circuit-interrupting means at each end thereof, said protective system including normally continuously operating sources of carrier current of different frequencies, normally continuously coupled to the line-section, one at each end thereof, means at each end of the line-section for selectively responding to the beat-frequency of the two carrier currents, means at each end of the line-section for temporarily interrupting the transmission of carrier from that end to the far end, but not interrupting the application of carrier from that end to the beat-frequency means at that same end, in response to predetermined abnormal line circuit conditions at said same end of the protected line-section, carrier-current circuit-interrupter controlling means at each end of the protected line-section for controlling the circuit-interrupting means at that end under the joint control of line-circuit conditions at that end and beat-frequency conditions at that end, and timing means responsive to a failure of beat frequency for a predetermined length of time for thereafter performing a predetermined function.

3. A carrier-current protective system for a transmission-line including a line-section having circuit-interrupting means at each end thereof, said protective system including normally continuously operating sources of carrier current of different frequencies, normally continuously coupled to the line-section, one at each end thereof, means at each end of the line-section for selectively responding to the beat-frequency of the two carrier currents, means at each end of the line-section for temporarily interrupting the transmission of carrier from that end to the far end, but not interrupting the application of carrier from that end to the beat-frequency means at the same end, in response to both the existence of fault-power conditions and the existence of a predetermined direction of power-flow in the protected line-section at said same end thereof, carrier-current circuit-interrupter controlling means at each end of the protected line-section for controlling the circuit-interrupting means at that end under the joint control of line-circuit conditions at that end and beat-frequency conditions at that end, and timing means responsive to a failure of beat frequency for a predetermined length of time for thereafter performing a predetermined function.

4. A carrier-current protective system for a transmission-line including a line-section having circuit-interrupting means at each end thereof, said protective system including normally continuously operating sources of carrier current of different frequencies, normally continuously coupled to the line-section, one at each end thereof.

5. A carrier-current protective system for a transmission-line including a line-section having circuit-interrupting means at each end thereof, said protective system including normally continuously operating sources of carrier current of different frequencies, normally continuously coupled to the line-section, one at each end thereof, means at each end of the line-section for responding to the direction of power-flow at its own end of the line-section, but making said response only in the event of fault-power conditions in the transmission-line, means at each end of the line-section for temporarily interrupting the transmission of carrier from that end to the far end, but not interrupting the application of carrier from that end to the beat-frequency means at that same end, in response to an actuation of a directional relay means at said same end of the protected line-section, carrier-current circuit-interrupter controlling means at each end of the protected line-section for controlling the circuit-interrupting means at that end under the joint control of an actuation of a directional relay means at that end and a condition of energization or non-energization of the beat-frequency means at that end, and timing means responsive to a failure of beat-frequency for a predetermined length of time for thereafter performing a predetermined function.

6. A carrier-current protective system for a transmission-system including a plurality of serially connected line-sections, switching stations between said line-sections, and circuit-interrupter means for each line-section in each station, said protective system including a plurality of normally continuously operating carrier-current generators tuned to different frequencies, a single carrier-current generator being disposed in each switching station, means at each station for superimposing the carrier-current on the transmission system, line-current-responsive directional means at the several stations for temporarily interrupting the transmission of carrier at the points where there exists a predetermined direction of flow of fault-power, the response in one station being in accordance with power-flow to the left, the response in the next station

being in accordance with power-flow to the right, and so on, in response to alternating directions of power-flow in succeeding stations, and carrier-channel receiver-means individual to each line-section at each station for selectively responding to the controlled application of carrier at the other end of the particular line-section in question, for exercising a controlling influence on the circuit-interrupter means for said line-section.

7. A carrier-current protective system for a transmission-system including a plurality of serially connected line-sections, switching stations between said line-sections, and circuit-interrupter means for each line-section in each station, said protective system including a plurality of carrier-current generators tuned to different frequencies, a carrier-current generator being disposed in each switching station, means at each station for superimposing the carrier-current on the transmission-system, the beat-frequencies between any carrier-current generator and the carrier-current generators at other stations along the line being different, so as to provide for selectivity, means for controlling the transmission of carrier at each end in accordance with line circuit conditions at that end, means, at each end of each line-section, selectively responsive to the beat-frequency of the two carrier-current sources at the opposite ends of that line-section, for obtaining an indication of the line circuit conditions at the other end of the line-section, and means for utilizing such indication in the control of the corresponding circuit-interrupter means.

8. A carrier-current protective system for a transmission-line including a line-section having circuit-interrupting means at each end thereof, said protective system including normally continuously operating sources of carrier current of different frequencies, normally continuously coupled to the line-section, one at each end thereof, means at each end of the line-section for selectively responding to the beat-frequency of the two carrier currents, "power-out" directional relay means at each end of the line-section for responding to the direction of power-flow out of the protected line-section at its own end thereof, but making said response only in the event of fault-power conditions in the transmission-line, "power-in" directional relay means at each end of the line-section for responding to the direction of power-flow into the protected line-section at its own end thereof, but making said response only in the event of fault-power conditions in the transmission-line, means at each end of the line-section for temporarily interrupting the transmission of carrier from that end to the far end, but not interrupting the application of carrier from that end to the beat-frequency means at that same end, in response to an actuation of said "power-out" directional relay means at said same end of the protected line-section, carrier-current circuit-interrupter controlling means at each end of the protected line-section for controlling the circuit-interrupting means at that end under the joint control of an actuation of said "power-in" directional means at that end and a continued actuation of the beat-frequency means at that end, and timing means responsive to a failure of beat frequency for a predetermined length of time for thereafter performing a predetermined function.

9. A carrier-current protective system for a transmission-system including a plurality of

line-sections, each having a terminal in a common bus at a certain switching-station, other switching station or stations at the other ends of said line-sections, and circuit-interrupter means for each line-section in each station, said protective system including a single carrier-current generator in said certain switching-station, other carrier-current generator or generators in said other station or stations, means for normally continuously coupling said carrier-current generators to said transmission-system, said certain switching-station also including a plurality of modulation-means of different distinctive modulation-frequencies, one for each line-section terminal associated with said common bus, means for separately controlling each modulation-means in accordance with predetermined line-circuit conditions in its own line-section, and carrier-channel receiver-means at the other ends of each of said line-sections for receiving the transmitted carrier wave, demodulating the same, selectively responding to the appropriate modulation-frequency, and utilizing said response in the control of the circuit-interrupter means at that end.

10. A carrier-current protective system for a polyphase transmission-line section, comprising two sources of carrier current coupled to the line-section, one at each end thereof, rotational-phase-sequence-responsive means at each end for controlling the transmission of carrier at its own end in accordance with line circuit conditions at that end, and means at each end, selectively responsive to the condition with respect to carrier-current transmission at the other end, unaffected by the condition with respect to carrier-current transmission at its own end, and jointly responsive also to a rotational-phase-sequence line-circuit condition at its own end, for protecting said line-section.

11. A carrier-current protective system for a polyphase transmission-line section, comprising two normally transmitting sources of carrier current coupled to the line-section, one at each end thereof, means for controlling the transmission of carrier at each end, phase-sequence-responsive means at each end of the line-section, for controlling said carrier-controlling means in response to a predetermined rotational-phase-sequence line-circuit condition at its own end, and means at each end, jointly responsive to the condition with respect to carrier-current transmission at the other end and to a rotational-phase-sequence line-circuit condition at its own end, for protecting said line-section.

12. A carrier-current protective system for a polyphase transmission-line section, comprising two normally transmitting sources of carrier current coupled to the line-section, one at each end thereof, means for interrupting the transmission of carrier at each end, phase-sequence power-directionally responsive means at each end of the line-section, for controlling said carrier-interrupting means in response to a rotational-phase-sequence line-circuit condition at its own end, which indicates the presence of a fault on the protected-line-section side of the phase-sequence power-directionally responsive means, and means at each end, selectively responsive to a failure of carrier-current transmission at the other end, unaffected by the condition with respect to carrier-current transmission at its own end, and jointly responsive also to a rotational-phase-sequence power-directional line-circuit condition at its own end, for protecting said line-section.

13. A protective system for a polyphase transmission-line section, comprising means for providing a communicating channel between the two ends thereof, two normally transmitting sources of signal current coupled to said communicating channel, one at each end thereof, a phase-sequence relay at each end of the line-section for interrupting the transmission of effective signal current at its own end in response to a predetermined rotational-phase-sequence line-circuit condition at its own end, and means at each end, jointly responsive to the condition with respect to signal-current transmission at the other end and to a rotational-phase-sequence line-circuit condition at its own end, for protecting said line-section.
14. A protective system for a polyphase transmission-line section, comprising means for providing a communicating channel between the two ends thereof, two normally transmitting sources of signal current coupled to said communicating channel, one at each end thereof, means for interrupting the transmission of signal current at each end, a phase-sequence relay at each end of the line-section for controlling said signal-current-interrupting means in response to a predetermined rotational-phase-sequence power-directional line-circuit condition at its own end, and means at each end, jointly responsive to the condition with respect to signal-current transmission at the other end and to a rotational-phase-sequence power-directional line-circuit condition at its own end, for protecting said line-section.
15. A carrier-current protective system for a polyphase transmission-line section, comprising two sources of carrier current coupled to the line-section, one at each end thereof, negative-phase-sequence-responsive means at each end for controlling the transmission of carrier at its own end in accordance with line circuit conditions at that end, and means at each end, selectively responsive to the condition with respect to carrier-current transmission at the other end, unaffected by the condition with respect to carrier-current transmission at its own end, and jointly responsive also to a negative-phase-sequence line-circuit condition at its own end, for protecting said line-section.
16. A carrier-current protective system for a polyphase transmission-line section, comprising two normally transmitting sources of carrier current coupled to the line-section, one at each end thereof, means for controlling the transmission of carrier at each end, phase-sequence-responsive means at each end of the line-section, for controlling said carrier-controlling means in response to a predetermined negative-phase-sequence line-circuit condition at its own end, and means at each end, jointly responsive to the condition with respect to carrier-current transmission at the other end and to a phase-sequence line-circuit condition at its own end, for protecting said line-section.
17. A carrier-current protective system for a polyphase transmission-line section, comprising two normally transmitting sources of carrier current coupled to the line-section, one at each end thereof, means for interrupting the transmission of carrier at each end, phase-sequence power-directionally responsive means at each end of the line-section, for controlling said carrier-interrupting means in response to a negative-phase-sequence line-circuit condition at its own end, which indicates the presence of a fault on the protected line-section side of the phase-sequence power-

directionally responsive means, and means at each end, selectively responsive to a failure of carrier-current transmission at the other end, unaffected by the condition with respect to carrier-current transmission at its own end, and jointly responsive also to a negative-phase-sequence power directional line-circuit condition at its own end, for protecting said line-section.

18. A protective system for a polyphase transmission-line section, comprising means for providing a communicating channel between the two ends thereof, two normally transmitting sources of signal current coupled to said communicating channel, one at each end thereof, a phase-sequence relay at each end of the line-section for interrupting the transmission of effective signal current at its own end in response to a predetermined negative-phase-sequence line-circuit condition at its own end, and means at each end, jointly responsive to the condition with respect to signal-current transmission at the other end and to a negative-phase-sequence line-circuit condition at its own end, for protecting said line-section.

19. A protective system for a polyphase transmission-line section, comprising means for providing a communicating channel between the two ends thereof, two normally transmitting sources of signal current coupled to said communicating channel, one at each end thereof, means for interrupting the transmission of signal current at each end, a phase-sequence relay at each end of the line-section for controlling said signal-current-interrupting means in response to a predetermined negative-phase-sequence power-directional line-circuit condition at its own end, and means at each end, jointly responsive to the condition with respect to signal-current transmission at the other end and to a negative-phase-sequence power-directional line-circuit condition at its own end, for protecting said line-section.

20. A carrier-current protective system for a transmission-line including a line-section having circuit-interrupting means at each end thereof, said protective system including normally continuously operating sources of carrier current of different frequencies, normally continuously coupled to the line-section, one at each end thereof, means at each end of the line-section for selectively responding to the beat-frequency of the two carrier currents, means at each end of the line-section for temporarily interrupting the transmission of carrier from that end to the far end, but not interrupting the application of carrier from that end to the beat-frequency means at that same end, in response to predetermined line circuit conditions at said same end of the protected line-section, carrier-current circuit-interrupter controlling means at each end of the protected line-section for controlling the circuit-interrupting means at that end under the joint control of line-circuit conditions at that end and beat-frequency conditions at that end, and timing means responsive to a failure of beat frequency for a predetermined length of time for thereafter performing a predetermined function.

21. A carrier-current protective system for a transmission-line including a line-section having circuit-interrupting means at each end thereof, said protective system including normally continuously operating sources of carrier current of different frequencies, normally continuously coupled to the line-section, one at each end thereof, means at each end of the line-section for selectively responding to the beat-frequency of the

two carrier currents, means at each end of the line-section for temporarily interrupting the transmission of carrier from that end to the far end, but not interrupting the application of carrier from that end to the beat-frequency means

5 at that same end, in response to the existence of a predetermined direction of power-flow in the protected line-section at said same end thereof, carrier-current circuit-interrupter controlling means at each end of the protected line-section 10 for controlling the circuit-interrupting means at that end under the joint control of line-circuit conditions at that end and beat-frequency conditions at that end, and timing means responsive to a failure of beat frequency for a predetermined length of time for thereafter performing a predetermined function.

24. A carrier-current protective system for a transmission-line including a line-section having 20 circuit-interrupting means at each end thereof, said protective system including normally continuously operating sources of carrier current of different frequencies, normally continuously coupled to the line-section, one at each end thereof, means at each end of the line-section for selectively responding to the beat-frequency of the two carrier currents, directional relay means at each end of the line-section for responding to the direction of power-flow at its own end of the line-section, means at each end of the line-section for temporarily interrupting the transmission of carrier from that end to the far end, but not interrupting the application of carrier from that end to the beat-frequency means at that same 25 end, in response to an actuation of a directional relay means at said same end of the protected line-section, carrier-current circuit-interrupter controlling means at each end of the protected line-section for controlling the circuit-interrupting means at that end under the joint control of an actuation of a directional relay means at that end and a condition of energization or non-energization of the beat-frequency means at that end, and timing means responsive to a failure of beat frequency for a predetermined length of time for thereafter performing a predetermined function.

25. A carrier-current protective system for a transmission-line including a line-section having 30 circuit-interrupting means at each end thereof, said protective system including normally continuously operating sources of carrier current of different frequencies, normally continuously coupled to the line-section, one at each end thereof, means at each end of the line-section for selectively responding to the beat-frequency of the two carrier currents, "power-out" directional relay means at each end of the line-section for responding to the direction of power-flow out of the protected line-section at its own end thereof, "power-in" directional relay means at each end of the line-section for responding to the direction of power-flow into the protected line-section at its own end thereof, means at each end of the line-section for temporarily interrupting the transmission of carrier from that end to the far end, but not interrupting the application of carrier from that end to the beat-frequency means at that same end, in response to an actuation of said "power-out" directional relay means at said same end of the protected line-section, carrier-current circuit-interrupter controlling means at each end of the protected line-section for controlling the circuit-interrupting means at that end under the joint control of an actuation of said "power-in" directional means at that end and a continued actuation of the beat-frequency means at that end, and timing means responsive to a failure of beat frequency for a predetermined length of time for thereafter performing a predetermined function.

26. A protective system for a polyphase transmission-line section having a line-conductor for each phase, said system comprising means for 65 providing a communicating channel between the two ends of the protected line-section, two normally transmitting sources of signal current coupled to said communicating channel, one at each end thereof, a relay at each end of the line-section, responsive only to an unbalance condition in the protected line-section, means at each end for interrupting the transmission of effective signal current at its own end in response to an actuation of said unbalance relay at that end, and 70 75

two carrier currents, means at each end of the line-section for temporarily interrupting the transmission of carrier from that end to the far end, but not interrupting the application of carrier from that end to the beat-frequency means at that same end, in response to the existence of a predetermined direction of power-flow in the protected line-section at said same end thereof, carrier-current circuit-interrupter controlling means at each end of the protected line-section for controlling the circuit-interrupting means at that end under the joint control of line-circuit conditions at that end and beat-frequency conditions at that end, and timing means responsive to a failure of beat frequency for a predetermined length of time for thereafter performing a predetermined function.

22. A carrier-current protective system for a transmission-line including a line-section having 20 circuit-interrupting means at each end thereof, said protective system including normally continuously operating sources of carrier current of different frequencies, normally continuously coupled to the line-section, one at each end thereof, means at each end of the line-section for selectively responding to the beat-frequency of the two carrier currents, directional relay means at each end of the line-section for responding to the direction of power-flow at its own end of the line-section, means at each end of the line-section for temporarily interrupting the transmission of carrier from that end to the far end, but not interrupting the application of carrier from that end to the beat-frequency means at that same end, in response to an actuation of a directional relay means at said same end of the protected line-section, carrier-current circuit-interrupter controlling means at each end of the protected line-section for controlling the circuit-interrupting means at that end under the joint control of an actuation of a directional relay means at that end and a condition of energization or non-energization of the beat-frequency means at that end, and timing means responsive to a failure of beat frequency for a predetermined length of time for thereafter performing a predetermined function.

23. A carrier-current protective system for a transmission-line including a line-section having 20 circuit-interrupting means at each end thereof, said protective system including normally continuously operating sources of carrier current of different frequencies, normally continuously coupled to the line-section, one at each end thereof, means at each end of the line-section for selectively responding to the beat-frequency of the two carrier currents, directional relay means at each end of the line-section for responding to the direction of power-flow into the protected line-section at its own end thereof, means at each end of the line-section for temporarily interrupting the transmission of carrier from that end to the far end, but not interrupting the application of carrier from that end to the beat-frequency means at that same end, in response to an actuation of said directional relay means at said same end of the protected line-section, carrier-current circuit-interrupter controlling means at each end of the protected line-section for controlling the circuit-interrupting means at that end under the joint control of an actuation of said directional means at that end and a continued actuation of the beat-frequency means at that end, and timing means responsive to a failure of beat frequency for a predetermined length of time for thereafter performing a predetermined function.

means, at each end, jointly responsive to the condition with respect to signal-current transmission at the other end and to a negative-phase-sequence line-circuit condition at its own end, for protecting said line-section.

27. In a polyphase transmission-line section having a line-conductor for each phase, and a circuit-interrupting means at each end thereof, a protective system for substantially simultaneously opening the circuit-interrupting means at both ends only in the event of such a fault-condition in the protected section as is accompanied by an unbalance between the currents in said line-conductors, said protective system comprising means for providing a communicating channel between the two ends of the protected line-

section, two normally transmitting sources of signal current coupled to said communicating channel, one at each end thereof, a relay at each end of the line-section, responsive only to an unbalance condition in the protected line-section, means at each end for interrupting the transmission of effective signal current at its own end in response to an actuation of said unbalance relay at that end, and means at each end, jointly responsive to the condition with respect to signal-current transmission at the other end and to a negative phase-sequence line-circuit condition at its own end, for controlling the circuit-interrupting means at its own end.

HERMANN NEUGEBAUER.
